(57) **CLAIM**

The ornamental design for an evacuated air chamber, as shown and described.

DESCRIPTION

FIG. 1 is a perspective view of an evacuated air chamber showing the new design;

FIG. 2 is a front elevation view, the rear elevation view, the right side elevation view and the left side elevation view being identical;

FIG. 3 is a top plan view thereof; and,

FIG. 4 is a bottom plan view thereof.

The broken lines in the drawings illustrate portions of the evacuated air chamber that form no part of the claimed design.
